UNITED STATES PATENT OFFICE.

LOUIS RAUHAUSER, OF BROOKLYN, NEW YORK.

HOISTING AND DREDGING BUCKET.

No. 926,132.

Specification of Letters Patent.

Patented June 29, 1909.

Application filed March 3, 1909. Serial No. 481,078.

To all whom it may concern:

Be it known that I, LOUIS RAUHAUSER, a citizen of the United States, and a resident of Brooklyn, in the county of Kings and 5 State of New York, have invented certain new and useful Improvements in Hoisting and Dredging Buckets, of which the following is a specification.

The invention relates to improvements in 10 hoisting and dredging buckets, and it consists in the novel features and combinations of parts hereinafter described, and particularly pointed out in the claims.

The object of the invention is to provide a 15 hoisting and dredging bucket of great durability and efficiency and one lacking in complexity and undue weight of material.

The bucket of my invention comprises two side plates, a bail or frame connecting said 20 plates, two pivoted oppositely disposed corresponding bucket sections and means for opening said sections in a direction from and closing them in a direction toward each other, said means for operating the bucket sections 25 comprising an upper vertically movable cross-head, a lower vertically movable cross-head, links pivoted at their outer ends to the upper outer ends of the bucket sections and at their inner ends to said upper cross-head, 30 links pivoted at their outer ends to the upper outer ends of the bucket sections and at their inner ends to said lower cross-head and sheaves and cables connected with said cross-heads for actuating them and the links connected with them to operate the bucket sections. 35

The invention will be fully understood from the detailed description hereinafter presented, reference being had to the accompanying drawings, in which:

Figure 1 is a vertical transverse section through a hoisting bucket embodying my invention, the section being on the dotted line 1—1 of Fig. 3; Fig. 2 is a corresponding view 45 of the same showing the bucket-sections spread apart; and Fig. 3 is a vertical section of the same on the dotted line 3—3 of Fig. 1.

In the drawings, 10 designates the two side plates of the bucket structure, 11 an inverted 50 U-shaped frame connecting the same, 12 the corresponding bucket sections pivoted, at 13, to said side plates, 14 the upper vertically movable cross-head, 15 the lower vertically movable cross-head, 16 links pivoted to said 55 upper cross-head and the upper outer ends of the bucket-sections, 17 links pivoted to said

lower cross-head and to the upper outer ends of said bucket-sections, 18 three sheaves carried by the lower cross-head, 19 two sheaves carried by the upper cross-head, and 20 a 60 cable which, as shown in Fig. 3, extends downwardly through the upper cross-head and around under the lower left hand sheave 18, thence upwardly and over the upper left hand sheave 19, thence downwardly under 65 the middle sheave 18, thence upwardly over the upper right hand sheave 19, thence downwardly under the lower right hand sheave 18, thence upwardly to a pin 21 on the upper cross-head 14 to which the cable is firmly 70 tied or otherwise fastened, and thence upwardly to the cable operating means, not shown. One member, 22, of the cable is free to travel over the sheaves of both cross-heads and the other member, 23, of said 75 cable is fastened to the upper cross-head, whereby what is in effect a pair of triple pulley blocks is created. Both members 22, 23 of the cable extend upwardly through a hole in the frame 11 and to means, not 80 shown, for alternately pulling on the cable-member 23 for opening the bucket-sections and on the cable-member 22 for closing said sections. The cable operating means will, as usual, be employed for raising and lowering 85 the bucket.

The bucket-sections 12 are exactly alike and each has sides and a downwardly curved bottom and is pivotally secured to the main side-plates 10 by short bolts 13 which pass 90 through said plates and the sides of the bucket-section. The bucket-sections have a hinged movement on the bolts 13 and these bolts are at intermediate points between the upper outer and lower inner ends of the 95 bucket-sections. The bucket-sections are each equipped with an inner bottom plate 24, which may be removed and renewed from time to time as may be required and whose purpose is to avoid as far as possible wear of 100 the material handled on the main bottom of the bucket-sections. Each bucket-section at its lower edge is provided with a durable bar 25 having a reasonably sharp outer edge and a reduced or shank inner portion which 105 is inserted between the main bottom plate and inner bottom plate 24. The bars 25 relieve the lower edges of the bucket-sections from wear and also facilitate the movement of said edges through the material to be 110 handled.

The vertical sides of the inverted U-shaped

frame or bail 11 afford guides 26 for the upper cross-head 14 and also for the lower cross-head 15 when the latter is in its upper position, shown in Fig. 1, said lower cross-head 5 when in its lower position passing below said guides, as shown in Fig. 2. The upper cross-head 14 is in the form of two parallel plates connected at their ends and at said ends engaging the guides 26 and having downwardly 10 extending arms 27 to which the inner adjacent ends of the links 16 are pivotally secured by means of bolts 28. The sheaves 19 are between the plates of the cross-head 14.

The lower cross-head 15 corresponds in 15 general construction with the upper cross-head 14 and at its ends is provided with the downwardly extending arms 29 to which the inner adjacent ends of the links 17 are pivotally secured by means of bolts 30. Since 20 when the bucket-sections are opened the lower cross-head passes below the guides 26, the ends of said cross-head are provided with the upwardly extending guide rods 31 (Fig. 3) which pass upwardly between the sides of 25 the upper cross-head and through holes in the top of the frame 11. The links 16, 17 are straight bars and at their outer ends are pivotally secured to the upper outer ends of the sides of the bucket-sections by means of 30 bolts 32.

When the bucket-sections 12 are in closed position the links 16, 17 at each side of the structure define a horizontal diamond-shaped outline, as shown in Fig. 1, and when the 35 bucket-sections are in an open position said links at each side of the bucket define a vertical diamond-shaped outline, as shown in Fig. 2, due to the separation of the inner ends of the pairs of links in a vertical direction 40 and the approach of the outer ends of said pairs of links in a horizontal direction.

In considering the operation of the bucket, it may be assumed that the latter is closed, as shown in Fig. 1. The bucket-sections 12 45 may be opened by pulling on the cable-member 23, then lowered to the material to be handled and then closed to take up a load of said material by a pulling force exerted against the cable-member 22. The pull on 50 the cable-member 23 while the cable-member 22 is released, is transmitted to the upper cross-head 14 and through said cross-head to the inner ends of the links 16, with the result that said cross-head and the inner ends 55 of said links are elevated and the lower cross-head 15 and inner ends of the links 17 are lowered, whereby the outer ends of the pairs of links 16, 17 are caused to approach each other and in doing so pull inwardly against 60 the upper outer ends of the bucket-sections to turn said sections on the bolts 13 and move the lower ends of said sections apart or to their open position. The bucket-sections will normally open until the bolts 28, 65 32, 13 and the lower edge of the bucket-sec-

tion at each side of the vertical center of the bucket structure are in line, and this feature I deem of importance since then when the lower edges of the bucket-sections engage the material there is a line of resistance from the 70 lower edge of each section up through the bolts 13, bolts 32, links 16 and bolts 28 against the cross-head 14 then against the top of the frame 11. In Fig. 2 the bucket-sections are shown abnormally open so as to 75 get them on the sheet.

When it is desired to close the bucket-sections on the material to be elevated, the cable-member 23 is released and a pulling force exerted against the cable-member 22, 80 with the result that the cross-heads 14, 15 are moved toward each other, pulling the inner ends of the pairs of links 16, 17 with them and forcing the outer ends of said pairs of links outwardly to turn the bucket-sections on the bolts 13 to their closed position 85 shown in Fig. 1. During the closing of the bucket sections their lower edges travel on arcs of circles whose centers are the bolts 13 and hence they force their way downwardly 90 into the material to be handled and take up a proper quantity thereof.

I prefer to construct the bucket-sections and main side-plates of sheet metal or rolled plate and will re-inforce the same at their 95 edges in any appropriate manner.

What I claim as my invention and desire to secure by Letters-Patent, is:

1. A hoisting and dredging bucket comprising sides, means connecting said sides, corresponding bucket-sections pivotally secured below their upper ends to said sides, upper and lower cross-heads between said sides, guides for said cross-heads, upper links pivoted to said upper cross-head and to the upper ends of the bucket-sections, lower links pivoted to the lower cross-head and to the upper ends of said bucket-sections, and means for causing said cross-heads to separate and approach each other 110 for actuating said links to open and close said bucket-sections, said links defining a horizontal diamond when the bucket-sections are closed and a vertical diamond when said sections are open; substantially 115 as set forth.

2. A hoisting and dredging bucket comprising sides, means connecting said sides, corresponding bucket-sections pivotally secured below their upper ends to said sides, 120 upper and lower cross-heads between said sides, guides for said cross-heads, upper links pivoted to said upper cross-head and to the upper ends of the bucket-sections, lower links pivoted to the lower cross-head and to the upper ends of said bucket-sections, and means for causing said cross-heads to 125 separate and approach each other for actuating said links to open and close said bucket-sections, said links defining a horizontal 130

diamond when the bucket sections are closed and a vertical diamond when said sections are open, the means for effecting the movement of said cross-heads comprising a series of sheaves carried by said cross-heads, a cable having a rigid connection with the upper cross-head for pulling the same upwardly to open the bucket-sections, and a cable fastened at one end to the upper cross-head and passing back and forth over the sheaves of both cross-heads and then upwardly for pulling on the lower cross-head to close the bucket sections; substantially as set forth.

15 3. A hoisting and dredging bucket comprising sides, means connecting said sides, corresponding bucket-sections pivotally secured below their upper ends to said sides, upper and lower cross-heads between said sides, guides for said cross-heads, upper links pivoted to said upper cross-head and to the upper ends of the bucket-sections, lower links pivoted to the lower cross-head and to the upper ends of said bucket-sections, and 20 means for causing said cross-heads to separate and approach each other for actuating said links to open and close said bucket-sections, said bucket-sections having inner pro-

teeting bottom plates (24) capable of renewal; substantially as set forth. 30

4. A hoisting and dredging bucket comprising sides, means connecting said sides, corresponding bucket-sections pivotally secured below their upper ends to said sides, upper and lower cross-heads between said sides, guides for said cross-heads, upper links pivoted to said upper cross-head and to the upper ends of the bucket-sections, lower links pivoted to the lower cross-head and to the upper ends of said bucket-sections, and 35 means for causing said cross-heads to separate and approach each other for actuating said links to open and close said bucket-sections, said bucket-sections having inner protecting bottom-plates (24) and edge bars 40 (25) having outer beveled edges and secured at their shank portions between the inner and outer bottom plates of the bucket-sections; substantially as set forth.

Signed at New York city, in the county of 50
New York and State of New York, this 2nd
day of March A. D. 1909.
